UNITED STATES PATENT OFFICE.

RALPH L. MORGAN, OF WORCESTER, MASSACHUSETTS, ASSIGNOR, BY MESNE ASSIGNMENTS, TO AMERICAN BICYCLE COMPANY, OF JERSEY CITY, NEW JERSEY, AND NEW YORK, N. Y., A CORPORATION OF NEW JERSEY.

FUEL-TANK AND MEANS FOR FILLING SAME.

SPECIFICATION forming part of Letters Patent No. 687,253, dated November 26, 1901.

Application filed September 8, 1900. Serial No. 29,381. (No model.)

To all whom it may concern:

Be it known that I, RALPH L. MORGAN, a citizen of the United States, residing at Worcester, in the county of Worcester and State of Massachusetts, have invented a new and useful Fuel-Tank and Means for Filling the Same, of which the following is a specification.

This invention relates to that class of fuel-tanks which are employed for holding gasoline or similar fuels in automobiles, gasolene-launches, or for other uses; and the especial object of this invention is to provide improved means for filling a fuel-tank without the loss of air-pressure therein and without exposing the gasolene or other fuel to the atmosphere, so as to incur the liability of explosion.

To this end this invention consists of a fuel-tank and of the combinations therewith of a special form of filling-can, as hereinafter described, and more particularly pointed out in the claims at the end of this specification.

In the accompanying drawings, Figure 1 is a side view, partially broken away, illustrating the manner in which a filling-can may be attached to the fuel-tank according to this invention. Fig. 2 is a sectional view of the upper part of the filling-can. Fig. 3 is a sectional view of a part of the filling-can and is taken on a plane at right angles to the plane of section of Figs. 1 and 2. Fig. 4 is a detail perspective view of the cap for closing the filling-opening of the fuel-tank. Fig. 5 is a fragmentary view illustrating the position of the valves while the fuel-tank is being filled. Fig. 6 is an enlarged fragmentary view illustrating a modified form of construction, and Fig. 7 is a detail view of the cap used in connection with the construction illustrated in Fig. 6.

In all places where gasolene or similar fuel is used under pressure considerable difficulty is encountered in refilling the fuel-tanks. This is especially the case in refilling the fuel-tanks of automobiles. In refilling the fuel-tank of the ordinary steam-automobile it is now impracticable to refill the fuel-tank without first extinguishing the burner, this necessity arising not only from the danger of igniting the fresh gasolene as the same is being

poured into the fuel-tank, but also arising from the fact that air-pressure is necessarily allowed to escape from the air-tank when the filling-orifice therein is opened to receive the fresh supply.

The especial object of my present invention is therefore to provide an improved construction which is especially designed for refilling the fuel-tank of an automobile without exposing any of the gasolene to the air and without materially diminishing the air-pressure in the fuel-tank.

To these ends this invention consists, essentially, of a special form of filling-can which can be detachably connected to the fuel-tank and of a valve mechanism which may be opened to permit the fuel-tank to be filled from the supply-can without material loss of pressure.

Referring to the accompanying drawings and in detail, A designates the fuel-tank, which may be provided with an ordinary air-inlet 10, to which a hand or power pump may be coupled to maintain air-pressure in the tank, a pressure of forty pounds or more being ordinarily required in the fuel-tank. The fuel-tank A, as illustrated, is also provided with an ordinary pressure-gage 11 and an outlet connection 12. A threaded spout or nipple 13 forms the filling-opening into the fuel-tank, and threaded into the spout 13 is a valve-seat 14, coöperating with which is a valve 15, which has its stem extending down through the guide 16, carried by suitable arms or a frame, as shown. The valve 15 is normally closed or seated by means of a coiled spring 17.

The supply-can B for filling the fuel-tank is preferably of substantially the same capacity as the fuel-tank itself. As herein illustrated, the supply-can B is provided with a threaded spout or neck 19 for permitting the supply-can to be detachably coupled to the fuel-tank A. Engaging a valve-seat inside the filling-can B is a valve 20, which extends through the guide 21 and is normally held closed or seated by a coiled spring 22. Extending up through the valve 20, and preferably passing through a small gland or stuffing-box therein, is a rod 23. An

operating-shaft 24 extends out through the side of the can through a suitable stuffing-box and is provided with a squared end for receiving a wrench. Secured on the inner 5 end of the operating-shaft 24 is an arm or lever 25. One arm of the lever 25 is connected by a rod or link 26 to operate the valve 20, and the other end of the lever 25 is connected to operate the rod 23. When the supply- 10 can is not in use, its spout or nose may be closed by a cap 28.

To fill the fuel-tank, the supply-can is first coupled thereto, as illustrated in Fig. 1. The operating-shaft 24 is then turned, so that the rod 23 will be pushed down to force the check-valve 15 of the fuel-tank from its seat, while at the same time the valve 20 will be lifted, as illustrated in Fig. 5. This will permit the gasoline or other fuel to flow from 15 the supply-can into the fuel-tank, and by means of this construction the fuel-tank A may be filled without exposing any of the gasoline to the air, so that all possibility of explosion will be absolutely avoided, and at 20 the same time the pressure in the fuel-tank will be maintained without substantial change, and on this account by practicing this invention the fuel-tank of an automobile may be easily refilled without extinguishing 25 the burner. When the supply-can is uncoupled from the fuel-tank, the filling-orifice of the fuel-tank may be closed by an ordinary cap, as 18, and the cap 28 may be also threaded onto the supply-can.

30 In some cases instead of employing the operating connections illustrated in the first sheet of drawings an operating cam or connection may be located in the neck of the filling-can, so as to directly engage and operate 35 the check-valves, and I have illustrated such a construction in the second sheet of drawings.

As shown in Fig. 6, the fuel-tank B may be provided with a filling spout or opening 30, mounted in which is a check-valve 31, having a stem 32 extending down through a guide, said valve 31 being normally held up to its seat by a spring 33. The filling-can B, as illustrated, is provided with a neck-piece or casting 35, which may be held in place by 45 a threaded collar 36. Mounted in the neck-piece 35 is a check-valve 37, having a stem 38 extending through a guide and being held normally to its seat by a spring 39 in the same manner as the check-valve 31 of the fuel- 50 tank. The check-valves 31 and 37 are provided with operating stems or projections 34 and 40, respectively. An operating-shaft 41 may be journaled in the neck-piece of the filling-can, so as to extend from one side 55 thereof in position to be operated by a wrench, in the same manner as the operating-shaft 24, previously described, and the operating-shaft 41 may be provided with a cam-section 42 for directly engaging the studs or projections of the check-valves, so that by turning 60 the operating-shaft the check-valves will be simultaneously opened to permit the fuel to

flow from the filling-can B into the fuel-reservoir A, as before described. When this form of construction is employed, the cap 70 43, which closes the filling-opening of the fuel-tank, is preferably provided with a recess, as indicated by dotted lines, which is deep enough to permit the cap to be partially threaded into place before depressing the 75 check-valve 31.

I am aware that numerous changes may be made in practicing my invention by those who are skilled in the art without departing from the scope thereof as expressed in the 80 claims. I do not wish, therefore, to be limited to the special construction which I have herein shown and described; but

What I do claim, and desire to secure by Letters Patent of the United States, is— 85

1. The combination of a fuel-tank for holding fuel under pressure, a supply-can, means for coupling said tank and can together, a check-valve in the outlet of the supply-can and a check-valve in the inlet of the fuel-tank, means for normally closing each of said valves, and means for opening said valves simultaneously whereby fuel may be conveyed from the supply-can to the fuel-tank without loss of pressure in the fuel-tank, substantially as described. 95

2. The combination of a fuel-tank for holding fuel under pressure, a supply-can, means for coupling said tank and can together so that the fuel will flow from the supply-can to the fuel-tank by gravity, a check-valve controlling the outlet of the supply-can and a check-valve controlling the inlet of the fuel-tank, means for normally closing each of said valves, and means in the supply-tank for opening said valves simultaneously when the supply-can and fuel-tank are coupled together to permit fuel to flow into the fuel-tank without loss of pressure therein. 105

3. The combination of a fuel-tank, a check-valve normally closing the filling-opening of the fuel-tank, a supply-can and check-valve normally closing the outlet of the supply-can, means for coupling the fuel-tank and supply-can together, an operating-shaft journaled in the supply-can, and two links operated from the shaft; one of said links being connected to open the check-valve of the supply-can, and the other of said links being connected to a rod arranged to open the check-valve of the fuel-tank, substantially as described. 115

4. The combination of a fuel-tank, a supply-can of substantially the same capacity as a fuel-tank, means for coupling the fuel-tank and supply-can together, a valve mechanism controlling the passage from the supply-can into the fuel-tank, and means for opening the valve mechanism to permit the liquid to run from the supply-can into the fuel-tank, whereby the fuel-tank may be filled 125 without loss of pressure and without exposing any of the liquid fuel to the air, substantially as described. 130

5. The combination of a fuel-tank, a check-

valve, normally closing the filling-opening of the fuel-tank, a supply-can and check-valve normally closing the outlet from the supply-can, means for coupling the supply-can and the fuel-tank in an inverted position, and operating connections for said check-valves, comprising a shaft journaled in the supply-can, an arm or cross-piece, a link extending from one end of the arm or cross-piece to lift

5 the check-valve of the supply-can, a link extending from the other end of the cross-piece,

10

and a rod extending therefrom through the check-valve of the supply-can into position to engage the check-valve of the fuel-tank, substantially as described.

15

In testimony whereof I have hereunto set my hand in the presence of two subscribing witnesses.
